DRAWING BOARD

Peter Seferow, New York, N. Y.

Application March 17, 1949, Serial No. 81,863

4 Claims. (Cl. 33—80)

1

The present invention relates to drawing boards, and more particularly to drawing boards having means for moving and retaining a straight-edge in parallel relation to the horizontal edges of the drawing surface.

Drawing boards, generally used by draftsmen, are provided with a straight-edge having pulleys, or the like, at the ends, which are guided by a cord, or cable, at each side of the board to maintain the straight-edge in parallel relation. One of the difficulties of such drawing boards is that the cords, due to their flexibility, stretch upon frequent use of the board, whereby the straight-edge acquires free play and no longer is accurately maintained in its parallel relation to the horizontal. This condition is further exaggerated where the cords are stretched or are loosened unevenly thereby tending to position the straight-edge at an angle to the horizontal edges of the drawing surface. This difficulty leads to the making of inaccurate drawings.

The present invention aims to overcome the foregoing difficulty by providing a drawing board wherein the straight-edge is positively maintained in its parallel relation by intermeshing means associated with the board and the straight-edge.

Accordingly, an object of the present invention is to provide an improved drawing board having a straight-edge combined therewith which is simple and economical in construction and can be readily operated without danger of disturbing its alignment.

Another object is to provide a drawing board of the foregoing character wherein the straight-edge may be pushed into desired approximate positions and operating means may be utilized for positioning the same more accurately.

Another object is to provide such operating means which are simple and practical and can be manipulated in a convenient manner.

Another object is to provide a drawing board of the foregoing character wherein a brake is associated with the operating means which serves to retain the straight-edge in desired positions of adjustment.

A further object is to provide hinge means for mounting the straight-edge between the moving and retaining means which facilitate placing the work between the straight-edge and the drawing surface.

Other and further objects will be obvious upon an understanding of the illustrative embodiment about to be described, or will be indicated in the appended claims, and various advantages not re-

2

ferred to herein will occur to one skilled in the art upon employment of the invention in practice.

A preferred embodiment of the invention has been chosen for purposes of illustration and description and is shown in the accompanying drawing, forming a part of the specification, wherein:

Figure 1 is a fragmentary plan view of a drawing board in accordance with the invention.

Figure 2 is a sectional view taken along the line 2—2 on Figure 1.

Figure 3 is a sectional view taken substantially along the line 3—3 on Figure 1.

Referring to the drawing in detail, there is shown a drawing board generally comprising a base 10, a frame member 11, at each side of the base, a top 12, a drawing surface 14 on the top, a straight-edge 15 above the drawing surface, and means in accordance with the present invention for moving and maintaining the straight-edge in parallel relation with the horizontal edges of the board, which means will be described in detail hereinafter.

The frame members are in the form of a channel having a lower flange 20, an upper flange 21, and a web 22, with a longitudinally extending slot 24, connecting the flanges. The lower flanges are mounted on and secured to the base 10 adjacent the side edges thereof and the upper flanges support the top member 12 and are secured thereto.

One of the flanges of each channel, preferably the lower flange 20 as shown, has a gear rack 25 mounted and secured thereon which extends substantially from end to end of the side members and length of the slot 24. A gear 26 is mounted on each gear rack and a rotatable shaft 27 has both gears secured thereto for rotation therewith. The ends of the shaft freely extend through the slots 24 and outwardly beyond the side frame members 11 for the purpose about to be described.

A plate 30 is provided at the outer side of each frame member which has a bearing aperture 31 through which the ends of the shaft 27 extend. The straight-edge 15 has its ends connected to the plates 30 to provide a movable carriage structure consisting of the gears 26, the shaft 27, the plates 30 and the straight-edge 15 which structure is in positive meshing relation with the gear racks 25 and hence is locked against being moved out of parallel alignment.

Preferably, the ends of the straight-edge 15 are connected to the plates 30 by a double hinge

arrangement comprising a member 35 secured to the plate, a member 36 hinged to the member 35, and a member 37 hinged to the member 36 and removably secured to the straight-edge by screws 38 or the like. This arrangement provides for slight upward and downward play of the straight-edge on the drawing surface without affecting its alignment whereby the work may be readily placed between the straight-edge and the drawing surface or removed.

The free ends of the shaft 27 are each provided with a manually engageable knob 40 to facilitate rotating of the shaft 27 whereby the gears 26 and gear racks 25 cooperate to effect movement of the straight-edge across the drawing surface.

In order to retain the straight-edge in desired positions of adjustment while working on the board, a brake is associated with one of the plates 30 and one of the knobs 40. This brake comprises an annular member 41 threaded on the shank of the knob, a friction disc 42 adjacent the plate 30, and a coil spring 44 disposed about the threaded shank and having its ends engaging the member 41 and the disc 42. The member 41 may be adjusted on the shank of the knob to vary the compression of the spring and its braking effect. In this manner, movement of the shaft 27 with respect to the plate 30 is prevented unless sufficient force is applied to rotate the knobs or push the straight-edge to overcome the friction established by the spring.

From the foregoing description, it will be seen that the present invention provides an improved drawing board having means for moving and maintaining the straight-edge in its desired alignment. The parts of the board are readily manufactured and assembled and can readily withstand such rough usage to which they may normally be subjected.

While the intermeshing means have been illustrated and described specifically in connection with gears on a shaft and gear racks, it will be appreciated that other equivalent mechanism may be utilized, such mechanism consisting of interconnected rotatable members cooperating with fixed track members.

As various changes may be made in the form, construction and arrangement of the parts herein, without departing from the spirit and scope of the invention and without sacrificing any of its advantages, it is to be understood that all matters are to be interpreted as illustrative and not in any limiting sense.

I claim:

1. A drawing board comprising a base, a channel member having the lower flange thereof mounted on said base and extending along each side thereof, said channel member having a lengthwise extending slot in the web thereof, a gear rack mounted on a flange of each channel member, a drawing surface mounted on the upper flanges of said channel members, a straight-edge member above said drawing surface having its ends adjacent the sides of said drawing surface, a gear for each of said gear racks, a rotatable shaft having said gears mounted thereon for rotation therewith, and having its ends extending outwardly through said slots, a bearing member adjacent the web of each of said channel members mounted on said shaft adjacent each end thereof, hinge means for connecting the ends of said straight-edge member to said bearing members, and a knob at one end of said shaft for effecting rotation thereof.

5 2. A drawing board comprising a base, a channel member having the lower flange thereof mounted on said base and extending along each side thereof, said channel member having a lengthwise extending slot in the web thereof, a gear rack mounted on a flange of each channel member, a drawing surface mounted on the upper flanges of said channel members, a straight-edge member above said drawing surface having its ends adjacent the sides of said drawing surface, a gear for each of said gear racks, a rotatable shaft having said gears mounted thereon for rotation therewith and having its ends extending outwardly through said slots, a bearing member adjacent the web of each of said channel members mounted on said shaft adjacent each end thereof, means for connecting the ends of said straight-edge member to said bearing members, a knob at one end of said shaft for effecting rotation thereof, and a brake including a spring coiled about said shaft between said knob and one of said bearing members for retarding rotation of said shaft with respect to said bearing member to thereby retain said straight-edge in a predetermined position with respect to said drawing surface.

30 3. A drawing board comprising a base, a channel member having the lower flange thereof mounted on said base and extending along each side thereof, said channel member having a lengthwise extending slot in the web thereof, a gear rack mounted on a flange of each channel member, a drawing surface mounted on the upper flanges of said channel members, a straight-edge member above said drawing surface having its ends adjacent the sides of said drawing surface, a gear for each of said gear racks, a rotatable shaft having said gears mounted thereon for rotation therewith, and having its ends extending outwardly through said slots, a bearing member adjacent the web of each of said channel members mounted on said shaft adjacent each end thereof, hinge means for connecting the ends of said straight-edge member to said bearing members, a knob at each end of said shaft for effecting rotation thereof, and a brake including a spring coiled about said shaft between one of said knobs and one of said bearing members for retarding rotation of said shaft with respect to said bearing member to thereby retain said straight-edge in a predetermined position with respect to said drawing surface.

45 4. A drawing board in accordance with claim 3 in which said hinge means includes a double hinge at each end of the straight-edge member.
